UNITED STATES PATENT OFFICE.

WILLIAM WILLERTON, OF HILLYARD, WASHINGTON.

ROTARY ENGINE.

Application filed September 18, 1920. Serial No. 409,924.

To all whom it may concern:

Be it known that I, WILLIAM WILLERTON, a citizen of the United States, residing at Hillyard, in Spokane County and State of Washington, have invented certain new and useful Improvements in Rotary Engines, of which the following is a specification.

My present invention relates to improvements in rotary steam engines of the compound type, employing a rotating member or rotor with steam operated swinging pistons and swinging abutments co-acting therewith under expansion of the fluid pressure.

The primary object of the invention is the provision of a simple and compact structure for this class of engines embodying novel features and combinations and arrangements of operating parts whereby the energy of the motive fluid is transmitted to the power shaft of the engine in an efficient and economical manner.

The invention consists essentially in the novel combination and arrangements of the swinging pistons carried by the rotor and complementary swinging abutments supported from the engine casing, and in details of construction complementary to these parts, as will be hereinafter described, for carrying out the purposes of the invention.

In the accompanying drawings I have illustrated one complete example of the physical embodiment of my invention, wherein the parts are combined and arranged according to the best mode I have thus far devised for the practical application of the principles of my invention.

Figure 1 is a longitudinal vertical sectional view of the engine on line 1—1 of Figure 2.

Figure 2 is a transverse vertical sectional view on the broken line 2—2 of Figure 1.

Figure 3 is a longitudinal vertical sectional view at line 3—3 of Figure 4 through the low pressure side of the engine.

Figure 4 is a transverse sectional view at line 4—4 of Figure 3, through a portion of the low pressure side of the engine.

The preferred form of the invention as illustrated in figures of the drawing contemplates the utilization of the usual cylindrical engine casing, of which the circular plate 1 forms the front wall, and the annular member or cylinder 2 forms the sides of the low and high pressure chambers, the casing being fixed or supported in suitable

manner by the integral flanges 3 of the cylinder. The back plate 4 of the casing is attached at the rear of the cylinder and the front plate is secured to the cylinder by transversely extending bolts 5 which clamp these parts together with steam-tight joints.

Within the cylinder are provided two annular spaces 6 and 7, the former for high pressure steam and the latter for low pressure motive fluid, the cylinder 2 providing the common outer wall for these chambers, and annular flanges 8 and 9 providing the respective inner walls of these high and low pressure chambers. The annular flange 9 forming the inner wall of the low pressure chamber is an integral part of the interior circular plate or disc 10, located between the rotor 11 and the rear wall of the engine casing, and adjustable for contact with said disc or rotor 11 by means of the central set screw or bolt 12 threaded through the rear wall 4 of the casing and bearing against the outer face of the circular plate 10.

The power developed from the energy of the steam in the engine is transferred and applied to its work by means of the power shaft 13 upon which the hub 14 of the rotor is splined or keyed, a collar 15 at the inner end of the shaft being employed to retain the rotor thereon. The shaft is revolvable in the fixed, central bearing sleeve 16 of the front plate of the casing, and a collar 17 on the shaft secures the joint against leakage.

Steam or other motive fluid under pressure is supplied to the engine through the main pipe 18 and two branch pipes 19 and 20 which are connected to their respective ports 21 and 22 drilled or bored transversely through the front plate, or through an integral boss 23 thereon.

The front plate is in the form of a ring with its annular flange 8 projecting inwardly, and the bosses 23 are formed at the inner periphery of the flange, with the inner annular face of the flange and the inner faces of the bosses in contact with the outer face of the flat disc or rotor 11. The ports 21 and 22 are inlet or entrance ports for steam, and open into one of a series of three valve-ports 24, 24', 24'', formed as annular grooves in the outer face of the rotor disc, and spaced from the axis of the shaft in position to travel around, and successively engage or register with the entrance ports 21 and 22 of the casing or its front plate. These valve ports, while the

rotor is revolving, intermittently receive motive fluid under pressure from the entrance ports, and establish communication while in register with the entrance ports 5 with complementary ports 25, 26 arranged in the bosses 23 and drilled parallel to the entrance ports 21, 22. The ports 25, 26, as indicated in Figure 2 are L-shaped and open, at the end of the radial passage 27 forming 10 part thereof, into the high pressure chamber 6 of the engine cylinder. The radiating passages 27 of the two ports 25 and 26 are arranged at diametrically opposite sides of the shaft, and the group of valve ports are 15 so situated with relation thereto to insure registration of two valve ports with the pairs of ports in the engine casing, in order that steam may be admitted to one portion of the high pressure chamber, while motive fluid is being cut off at a diametrically opposite point in said chamber.

The rotor revolves clockwise, and carries diametrically opposed swinging pistons or blades 28, 29, and 30 the free ends of which 20 sweep around in contact with the inner peripheral face of the wall 2 of the high pressure chamber and are held in this position by motive fluid pressure as indicated in 25 Figure 1. Near its outer edge the rotor is provided with a socket 30' for each piston 30 and the blades each have a boss 31 oscillatable in a socket, the blades conforming to the cross area of the annular chamber 6 and making a close frictional joint with its 35 four walls. The piston blades are provided with shoulders 32 which bear upon the peripheral surface of the outer wall of the chamber and hold them in proper contact with the inner wall thereof.

40 In close proximity to the steam ports 25, 26 or their radial passages 27 are arranged a pair of swinging abutments as 33 and 34, which are stationary relative to the swinging piston blades, but oscillatable on bosses 45 35 in sockets 36 in the front plate of the casing. The bosses 35, which are located at the inner side of the chamber 6 permit the free ends of the abutments to swing into contact with the wall 2 or outer periphery of the 50 chamber, and shoulders 37 on these abutments bear against the flange 8 of the front plate to afford a support thereagainst and limit the movement of the abutments. It will be noted that the abutments are pivoted by their bosses at the inner side of the 55 chamber 6 with their free ends in contact with the outer wall of the chamber, while the swinging pistons are pivoted on their bosses at the outer wall of the chamber 60 with their free ends in contact with the periphery of the annular flange 8 of the front plate. As the rotor revolves from pressure of steam admitted to the high pressure chamber 6, as through passage 27 to the 65 space between piston 29 and abutment 34

in Figure 1, it will be apparent that the expansion of steam will force and hold the abutment in the position shown while the pressure exerted against the swinging piston 29 will force its free end into contact with the outer periphery of the annular flange 8. Under pressure on the piston 29 the rotor is revolved, the piston traveling around its circular path until its free end contacts with the free end of the abutment 33. The piston passes over the abutment with a wiping action of their faces, each element being swung on its pivot, after which the abutment, by gravity, returns to the position shown in Figure 1. The piston remains idle as it passes through the lower portion of the chamber 6, but again swings to its original position, passing over the abutment 34 and uncovering and passing over the passage 27 from port 25. The 80 period for entrance of live steam at high pressure to the space between the piston 29 and abutment 34 extended during the time required for the valve groove 34' in the rotor to swing around while in register 85 with the two ports 21 and 25, and as the valve groove passed out of register therewith the steam supply was cut off.

At the lower side of the chamber 6 in Figure 1, steam is about to be cut off from the valve groove 24 as it passes from register with the ports 22 and 26, but the action described between piston 29 and abutment 34 has already taken place between the piston 30 and abutment 33.

The same action will be repeated as the piston blade 28 passes under ports 22 and 26 subsequent to its passage under abutment the abutment 32, and this piston will receive steam from the valve groove 24^a at the left 105 in Figure 1. In this manner a succession of three impulses are given with each rotation or revolution of the rotor, and as the speed of the rotor increases the action of the pistons increases resulting in a continuous and 110 uniform rotation of the rotor in its casing.

Following the described action of the piston 29 in its passage through the high pressure chamber, it will be evident that the high pressure, expanded steam, following 115 this piston, is cut off by the abutment 33 after said piston has passed said abutment.

This expanded steam is now transferred to the low pressure chamber 7 by way of a transfer duct 38 formed in the transversely extending, obliquely arranged, spoke, or bar 39 cast integral with the annular flange 8 and a complementary duct 40 is also provided in this transverse bar. The ducts 38 and 40 form a continuous passage with its opposite open ends communicating with the high pressure chamber 6 at diametrically opposite points and this passage is intercepted at the axial center of the engine by a T-shape channel 41, the longer leg of which 130

is bored from the inner end of the shaft 13, and extends along its axial center. The channel 41 opens into a low pressure steam chest 42, which is a cylindrical space formed 5 between the interior plate 10, the annular flange 9 and the rotor, at the side of the high pressure chamber and within the low pressure chamber 7.

Radially extending, diametrically opposed 10 low pressure ports 43 and 44 establish communication between the steam chest and the low pressure chamber 7, and exhaust ports 45 and 46 in the interior plate 10 pass the exhaust steam from the low pressure chamber 15 to exhaust pipes 47 and 48 that enter through the rear wall 4 of the engine casing and are connected to the main exhaust pipe 49 as seen in Figure 4.

Within the low pressure steam chamber 20 are arranged a group of three swinging pistons 50, 51, 52, and a pair of diametrically disposed swinging abutments 53 and 54, the former pivoted near the outer edge of the rotor in sockets on the opposite side of the rotor from the sockets 30' for the high pressure pistons, and the abutments 53 and 54 are pivoted in the inner face of the interior plate 10. The action of the pistons and abutments in the low pressure chamber is 25 the same as those in the high pressure chamber, but as shown in dotted lines Figure 1 the groups of pistons are relatively arranged in order that the six pistons occur at six regularly spaced intervals about the peripheral edge of the rotor thus distributing the 30 application of power thereto and insuring a uniform and smooth running of the engine.

It will thus be apparent that the full force 35 of the steam or motive fluid fed to the engine at the high pressure side is utilized and compounded, and the exhaust steam expanded to approximately atmospheric pressure, is disposed of after operating in the low pressure chamber of the engine.

The interior plate 10 and its flange 9 may be adjusted by turning the bolt 12 to take up wear, and the annular face of the flange which bears against the low pressure side 40 of the rotor may, in this manner, be kept in close contact with the rotor. A packing

ring 55 for the peripheral edge of the rotor is seated in an annular groove in the cylinder wall 2, and said wall is provided with an annular shoulder 56 against which the 45 face of the rotor, at the high pressure side of the engine, contacts and is held by action of the adjusting bolt 12.

In Figure 3 a piston and an abutment are shown in position they occupy when the former is passing the latter, and it will be understood that the pistons, except when under pressure of steam, are free to swing on their pivots under action of gravity, as are also the swinging abutments. But under 50 steam pressure in both chambers, the pistons and abutments are retained in closed position in the chambers, and the pistons sweep around in their chambers with their free 55 ends in contact with the inner walls of the 56 chambers.

Having thus fully described my invention, what I claim and desire to secure by Letters Patent is—

1. The combination with an engine casing, 75 a shaft and a circular disk having a hub fixed on said shaft and forming a rotor, of an inner flange on the front wall of the casing forming an annular steam chamber at one side of said rotor, co-acting pistons 80 and abutments in said chamber, said rotor having a series of spaced arcuate valve-grooves, and said casing having entrance valves for steam co-acting with said valve grooves, as described. 85

2. The combination in a rotary engine with its shaft, a circular disk having a hub fixed to said shaft and forming a rotor, said rotor and casing forming an annular steam chamber and co-acting pistons and abutments in the latter, of means for intermittently introducing steam to said chamber comprising a series of spaced arcuate grooves in the rotor, a pair of diametrically arranged entrance ports in the casing and a 90 steam supply thereto, and complementary steam ports for establishing communication between the respective grooves and said chamber. 95

In testimony whereof I affix my signature.

WILLIAM WILLERTON.
